DIAGNOSTIC INSTRUMENT

Walter A. Arnesen, New York, N. Y.

Application April 19, 1933, Serial No. 666,835

14 Claims. (Cl. 128—9)

This invention relates to improvements in diagnostic instruments and more particularly to improvements in illuminated diagnostic instruments.

5 In making an aural, urethral, proctoscopic and similar examinations, it is customary to make use of a suitable instrument provided with illumination for aiding in the examination. Various types of illuminating mechanisms have been utilized, but considerable disadvantages reside in the majority thereof. In some types of devices, it is necessary to make use of a prism for bending the rays of light into proper direction. In other types of devices, rays directly from a 10 source are utilized, but again it becomes necessary to provide some arrangement to prevent other rays from affecting the line of sight of the one making the examination. Special sources of rays become necessary, such sources in the 15 majority of cases being relatively expensive and of delicate nature.

An object of the invention is to provide a new, simple, inexpensive, and efficient light mechanism for use in connection with diagnostic instruments.

Another object of the invention is to provide an illuminating mechanism of such a character that ordinary flashlight electric bulbs can be used therein.

30 A further object of the invention is to provide illuminating mechanism for diagnostic instruments of such a character that concentrated rays directly from the filament of a flashlight bulb are thrown into the region to be examined 35 without interfering with the line of visual inspection.

A further object of the invention is to provide a diagnostic instrument carrier of such a character that the improved illuminating mechanism 40 of the invention can be consolidated therewith.

Another object of the invention is to provide diagnostic instrument carriers with arms extending substantially parallel to the line of direction of light rays which are projected toward 45 the area to be examined.

Still another object of the invention is to provide a socket for diagnostic instruments of such a character that the instruments are held in position by frictional contact.

50 Another object of the invention is to provide an instrument carrier of such type that tongue depressors of different sizes and shapes can be secured thereto.

A still further object of the invention is to provide an attaching member for diagnostic instruments, which member adapts the instrument to be used as an insufflator.

The illuminating mechanism of the present invention consists of a tubular member having a 55 socket in one end thereof for the reception of an 60

electric light bulb of the type ordinarily used in hand flashlights. Associated with this tubular bulb carrier is a lens cap in the nature principally of a closed end tube, through the top of which extends a smaller tube having one end closed and having a condensing or collecting lens mounted in the other end thereof. This smaller tube extends preferably at an angle of 110 degrees to the axis of the tube through which it passes. Due to this construction, the closed 10 end of the cap when inserted upon the bulb carrying tube rests directly upon the bulb so that the filament of the bulb is in position to project light rays directly against the condensing lens. Consequently, the rays projected from the lens 15 carrying tube are of maximum intensity and are substantially shadowless. Since the cap is rotatable relative to the bulb carrying tube, these parts can be rotated so that the filament is positioned most advantageously relative to the condensing lens. 20

In conjunction with this type of illuminating mechanism, use is made of diagnostic instrument carriers of various types, all of which, however, possess some common features of construction. 25 All types of carriers will have as a part thereof a hollow tubular member of such internal diameter as to fit closely around the bulb carrying tube and the lens cap. Set screws or other locking means are provided to fasten both carrying tube 30 and the lens cap in whatever position is desired. Extending outwardly from the hollow tubular member of the instrument carrier is an arm. In one type of carrier this arm is a simple bar having an elbow at one end thereof, which elbow 35 is connected directly with a ring-like socket for the reception of diagnostic instruments such as auriscopes, proctoscopes and the like. The elbow and the connection of the ring-like socket are split so that the socket can be expanded a slight 40 amount whereby the resiliency thereof will serve to retain the instrument by frictional contact. The only requirement is that the instrument have an annular portion of external diameter slightly 45 greater than the minimum internal diameter of the ring-like socket member. This arm extends outwardly in a plane substantially parallel to the axis of the lens carrying tube, while the ring-like socket member extends substantially at right angles to the arm. Due to this arrangement, it 50 is possible to raise or lower the light mechanism relative to the instrument held in the socket until the proper illumination can be secured. In this manner compensation may be made for variations in length and diameter in the diagnostic instruments. At the same time visual inspection is not interfered with and as is customary, use 55 may be made of a magnifying lens to aid such examination. In this arrangement the magnifying lenses whether they be of simple character 60

- or telescopic character, are supported on the closed end portion of the light carrying tube. The magnifying lens holder may be made if desired in the shape substantially of a figure 8, 5 with one loop split so that this loop becomes resilient enough to firmly grip the tube.
- When examination with a diagnostic instrument located in the ring-like socket requires insufflation, use may be made of the attachment 10 shown in the drawing, which attachment consists of a cylindrical member having a clear transparent window secured therein in an inclined position. One end of the cylinder is externally threaded for engagement with internal 15 threads provided in the annular portion of the diagnostic instrument gripped by the socket member. In order that air or gas can be introduced into the chamber formed by the diagnostic instrument and the cylinder, an aperture is provided in the window into which aperture is fitted one end of a small tube fastened to the wall of the cylinder. The other end of the tube is bent into an elbow and is provided with a nipple for the attachment of the customary rubber tubing. This 20 insufflator attachment is secured to the diagnostic instrument after the instrument has been seated in its socket, so that no change of focus is effected by this attachment, with the result that the inclined window can be of plain transparent glass.
- In some other types of insufflators at present known to the art, the attachment necessarily causes a change of focus with the result that the window must be a special prepared lens, usually 25 of negative value.
- In another type of instrument carrier, the arm which extends from the tubular portion is in the nature of a bowed plate having its side edges bent downwardly to form flanges through which is secured a pin. A two-ended leaf spring member 30 is held at an intermediate point by the pin so that the ends are forced directly against the bowed plate. A tongue depressor, usually of wood, of any ordinary size and shape can be firmly held by this instrument carrier, the only manipulation 35 necessary being a simple sliding of one end of the tongue depressor between the curved plate at the top, and the two ends of the leaf spring at the bottom. When so introduced, the tongue depressor is held against undesired movement and 40 can be removed readily by simple withdrawal from engagement with the carrier. Here again the arm, which is the bowed plate, extends from the tubular part of the carrier in a plane substantially 45 parallel to the axis of the lens carrying tube.
- In use, the illuminating mechanism can be raised or lowered to any desired position for best illumination of the mouth or throat of the patient, or even if desired, the lens cap can be made to illuminate portions of the patient's mouth out 50 of line with the tongue depressor.
- Other features and advantages of the invention will become apparent by reference to the following detail description read in the light of the accompanying drawing, wherein
- Fig. 1 is a side view of an embodiment of the invention showing the illuminating device combined with an instrument carrier.
- Fig. 2 is a different view of the same assembly.
- Fig. 3 is an enlarged section taken substantially on the line 3—3 of Fig. 2.
- Fig. 4 is a view of separate parts which are combined in the invention.
- Fig. 5 is a view of another modification of the invention showing the illuminating mechanism combined with an instrument carrier of slightly

different character from that of the previous figures.

Fig. 6 is a section taken substantially on the line 6—6 of Fig. 5.

Fig. 7 is a section taken substantially on the line 7—7 of Fig. 5.

Fig. 8 is a section taken substantially on the line 8—8 of Fig. 1; and

Fig. 9 is a fragmentary section of a cylindrical attachment utilized with the form of the invention shown in Figures 1 to 4 inclusive, when it is desired to provide insufflation.

Referring now to the drawing and particularly to Figures 1 to 4, inclusive, 10 indicates a cylindrical member made of some suitable metal which is provided at one end with a socket for the reception of an electric light bulb 11 of the character commonly used in flashlights. The other end of the member 10 is provided with threads 12 and a contact 13, this end of the member being adapted to make threaded engagement with an internally threaded contact element 14. As shown in Fig. 3, the member 10 is made as a hollow member and has positioned therein an insulator 15 through which extends a contact rod 16 carrying the contact 13 on one end thereof. A second contact 17 is secured to the end of a rod 18 around which is coiled a spring 19. The enlarged part of the contact element 16 is hollowed out for the reception of the rod 18 while the spring 19 has one end secured directly to the upper end of the member 16. An insulating disk 20 serves to maintain the contact 17 in proper alignment.

The contact member 14 is constructed in a manner similar to the arrangement just previously described in that it is provided with an insulator 21 through which extends a contact member 22. A contact 24 secured to a rod 25 is positioned with the member 14. A spring 26 is coiled around this rod 25 while a disk 27 of insulating material serves to align the contact 24 and also to prevent shorting thereof. An electric conductor 28 is secured to the lower end of the contact 22 as at 29, while the other conductor 30 is secured as by soldering to a sleeve 31 fitting closely within the lower end of the member 14. Thus one conductor is in effect grounded to the instrument itself while the other conductor is insulated from the instrument.

Associated with the member 10 is a lens cap indicated generally at 35, such cap being made up of a tubular portion 36 of size to fit around the upper part of the member 10. A smaller tubular section 37 extends outwardly from the cap 35 at an angle of substantially 110 degrees from the axis of the portion 36. A similar smaller tubular portion 38 extends from the opposite side of the member 36. If desired the members 37 and 38 may be formed from a single tube of material passing through the top of the closed-end tube 36. The outer end of the member 38 is closed as at 39. A condensing lens 40 is secured in the outer end of the tubular part 37 for a purpose to be explained hereinafter.

The member 38 serves as a support for a lens mount of suitable character. In the form illustrated, the lens mount 41 is in the shape substantially of a figure 8 with the lower loop split as at 42. A magnifying lens 43 is mounted in the upper loop of the lens holder. The internal diameter of the lower loop of this holder is slightly less than the diameter of the lens mount 41, so that due to the split 42 the lower loop can be forced upon the member 38, and when so positioned will be held thereon by frictional contact.

The invention, of course, is not to be limited to this type of lens holder or by this particular type of magnifying lens, since with certain types of diagnostic instruments it will be necessary to 5 make use of telescopic lenses. These lenses, naturally, can be mounted in a support which can fit around the member 38.

The tubular section 36 of the lens cap 35 is of such length that when it is slipped over the electric lamp 11 the top of the cap can rest directly 10 upon this lamp, as shown in Fig. 3. A part of the member 10 is of reduced diameter as shown to accommodate the cap, so that when the cap is in place, it and the enlarged part of member 10 15 have exterior surfaces which are in substantial alignment. The cap can be moved longitudinally on the member 10 to cause the lens therein to become properly focused relative to the filament of a light bulb, such movement being desirable 20 due to variations in filament positions in different bulbs.

In conjunction with this type of illuminating mechanism, use is made of diagnostic instrument carriers of different types as shown in the drawing. Each carrier, however, has parts which are 25 identical in construction. These parts consist of a hollow tubular member 50 having an upper rib 51 and a lower rib 52. The upper rib 51 has a threaded aperture therein in which fits a set screw 54. The lower rib 52 has a threaded 30 aperture therein in which fits a set screw 55. These parts of the instrument carriers are similar and are given the same reference characters in all figures of the drawing.

35 In the carrier shown in Figures 1 to 3, inclusive, an arm 56 extends angularly upwardly from the rib 51 in a plane substantially parallel to the axis of the tubular parts 37 and 38, or in other words, at an angle of substantially 40 110 degrees relative to the axis of the tubular part 50. The arm 56 has an elbow part 57 which is split as shown at 58 in Fig. 8, and which is enlarged into a ring 59. This split in the elbow extending upwardly through the ring part 59 45 permits a slight expansion of the ring so that diagnostic instruments can be forced into the ring to be held by frictional contact.

In conjunction with this ring-like socket, use 50 may be made of a diagnostic instrument of the type shown in Figures 1 and 2, or of any other suitable type, varying in length and diameter from that shown. The instrument illustrated is included as being merely illustrative of the uses to which the carrier can be put without intending any limitation whatever on the device. This instrument as shown has a funnel-like part 60, a flange 61 and an annular part 62. This annular part 62 is of such external diameter that when it is inserted into the ring-like socket, it 60 will spread the ring an amount sufficiently to cause the spring action thereof to grip the part 62 firmly. The interior of this part 62 is threaded as indicated at 64 in Figure 2 for a purpose to be explained hereinafter.

65 In the form shown in Figures 5 to 7, the rib 51 has extending outwardly therefrom a tongue depressor carrier in the nature of a bowed metallic arm 65 which is substantially parallel to the axis of the members 37 and 38. The edges 70 of arm 65 are bent downwardly as at 66 and a pin 67 extends through both parts 66, being locked to these parts in any suitable manner. A leaf spring 68 is bowed as shown in Figure 5 and is provided with a central depression 69 which fits 75 under the pin 67. The ends of the spring 68

are forced toward the bowed metal member 65. A tongue depressor 70 of some suitable material (preferably wood), can be inserted between the ends of the spring 68 and the bowed top 65 as shown in Figures 5 to 7.

The use and operation of the mechanism hereinbefore described is substantially as follows: Regardless of the type of instrument carrier used, the operation will be the same. The member 10 is screwed into engagement with the contact member 14 and an electric light bulb 11 is seated in the top of the member 10. This member 10 can then be inserted into the tubular member 50 until the light bulb extends above the upper edge of the member 50. The lens cap 35 is then placed in position shown in Figure 3, part thereof naturally fitting within the tubular member 50. If an instrument carrier of the type shown in Figures 1 to 3 is used, the light carrier and the lens cap are moved until the condensing lens 40 in the member 37 is in proper position to illuminate the opening in the instrument 60. Proper positioning of the light carrier will be aided materially by energizing the bulb 11 while the adjustment is being made. 25 When the light carrier has been positioned at the proper height relative to the member 50, it can be locked in place by tightening the set screws 54 and 55. Set screw 54 serves to lock the lens carrier in place while set screw 55 serves 30 to lock the member 10 in place. With a magnifying lens 43 in position, examination may be made through the instrument held in the instrument carrier. In practice, it has been found that the lamp carrier can be adjusted to illuminate 35 portions of the anatomy being examined through the diagnostic instrument without interfering with the inspection thereof through the proper magnifying lens. This is due primarily to the angle at which the tubular members 37 and 38 extend relative to the member 36 of the lens cap and also due to the fact that the arm 56 is substantially parallel to the axis of members 37 and 38 while the socket 59 is at substantially 40 right angles to the arm 56.

If insufflation is desired, use may be made of an attachment similar to that shown in Figure 9. This attachment consists of a parallel cylindrical member 70 provided with threads 71 at one end thereof, and provided with an inclined 50 window 72 of plain transparent glass. The window 72 can be positioned in the cylinder 70 in any desired manner so long as the arrangement provides an airtight seal around the window. An opening 74 is provided in the window near the 55 wall of the cylinder 70 into which opening fits an end of a tube 75 secured to the wall of member 70 in any suitable manner, such as by soldering. The tube 75 is provided with an elbow and with a nipple 76 at the end thereof for the attachment of rubber tubing. The threads 71 are designed for engagement with the threads 64 in the interior of the annular part 62 of the diagnostic instrument. Thus with this diagnostic instrument in place the insufflator attachment 60 can be secured thereto by merely engaging threads 64 and 71. A shoulder 77 on the cylindrical member 70 aids in forming an airtight seal with the end of the member 62.

The advantage of this type of insufflator attachment resides in the fact that it can be attached to a diagnostic instrument without affecting the focus of the light rays and of the magnifying lens through which the examination is carried out. Since the focus is not affected in 75

any way, it is not necessary that the window 72 be other than plain transparent glass.

If it becomes desirable to use a tongue depressor with illumination, the carrier shown in Figures 5 to 7 is used, the members 10 and 35 being fastened within the tubular part 50 of this carrier in the manner just previously described. The condensing lens with the light bulb directly therebehind can be raised or lowered to effect the desired illumination of the patient's mouth or throat when the depressor is in use. If desired the member 10 can be fastened permanently in part 50 or even made integrally therewith.

The illuminating device of this invention possesses the advantages not found in prior art instruments. Due to its construction it is possible to utilize ordinary flashlight bulbs which can be purchased at a very moderate cost. Furthermore, due to the fact that the lens cap can be adjusted to cause the filament of this bulb to be in a direct line with the condensing lens, the greatest quantity of rays from the filament can be projected outwardly in concentrated form by the condensing lens. Since the cap and the filament carrier are rotatable independently of each other when in position within the member 50 of an instrument carrier, it is possible to properly align the condensing lens with the diagnostic instrument, and then if desired, the lamp carrier can be moved until the filament is in the most favorable position relative to the condensing lens, thereby eliminating objectionable shadows.

The instrument carrier which is utilized as a holder for a tongue depressor, possesses advantages in that it is of such size as to accommodate tongue depressors of varying sizes. Since the actual tongue depressor is held firmly by the action of the spring in the carrier, no adjustment of set screws or of any other fastening mechanism is necessary. Consequently, a tongue depressor can be positioned in the carrier with maximum simplicity and can be removed therefrom with equal ease.

In both types of instrument carriers shown, it will be noted that the actual instrument will extend at a particular angle from the tubular part of the carrier. This angle which has been mentioned as being approximately 110 degrees, is the angle which makes it possible to utilize an illuminating device in which rays are projected outwardly in a line from the source of the rays. This angle also makes it possible to utilize direct rays without interfering with the visual inspection with that part of the anatomy under examination by the user.

The ring socket of the instrument carrier has the advantage that careful machining of parts of diagnostic instruments to fit the sockets is eliminated due to the split in the connection of the ring to the arm through the elbow, which imparts some degree of resiliency to the ring. Consequently, the diagnostic instrument can be inserted into the ring socket and held therein by frictional contact so long as the exterior diameter of the diagnostic instrument is slightly greater than the minimum internal diameter of the ring-like socket.

The provision of threads in the internal end of the diagnostic instrument makes it possible to use the insufflator attachment in Fig. 9 in conjunction with these diagnostic instruments by the mere threading of the attachment into the instrument without changing the focus of the set-up in any fashion.

From the foregoing, it will be seen that the present invention provides a combined illuminating mechanism and diagnostic instrument carrier which is capable of many and varied uses, and which can be modified to a considerable extent. In view of this it is to be understood that the claims are not to be limited to the illustrated embodiments but are to be limited only by the scope of the following claims.

I claim:

1. A device of the type described comprising a diagnostic instrument carrier, a member having a light bulb secured directly to and extending beyond one end thereof, means fitting over said bulb for projecting light rays directly therefrom in any upwardly and outwardly inclined direction relative to said member, means for adjustably securing said light projecting mechanism to said instrument carrier, and an arm extending from part of said carrier in a direction substantially parallel to the axis of the projected light rays.

2. A device of the type described comprising a diagnostic instrument carrier, a member having a light bulb secured directly to and extending beyond one end thereof, a lens cap fitting over said bulb and having therein a condensing lens for projecting light rays directly from said bulb in an upwardly and outwardly inclined direction relative to the axis of said member, said lens cap being slideable longitudinally of and rotatable about said member, means for adjustably securing said lens cap to said instrument carrier, an arm extending from part of said carrier in a direction substantially parallel to the axis of the projected light rays, and a resiliently expandable ring-like socket extending substantially at right angles from said arm for the reception of annular portions of instruments, said socket holding instruments in the path of projected light rays.

3. A device of the type described comprising a diagnostic instrument carrier, a member having a light bulb secured directly to and extending beyond one end thereof, means fitting over said bulb for projecting light rays directly therefrom in an upwardly and outwardly inclined direction relative to said member, means for adjustably securing said light projecting mechanism to said instrument carrier, an arm extending from part of said carrier in a direction substantially parallel to the axis of the projected light rays, a resiliently expandable ring-like socket extending substantially at right angles from said arm and an instrument having an annular part in engagement with said socket, said annular part of said instrument being internally threaded for the reception of an externally threaded cylinder having an inclined window therein and having a tube in communication with a part thereof through the opening in said window.

4. A device of the type described comprising a diagnostic instrument carrier, means at the top of said carrier for directing light rays outwardly from the carrier, an arm extending from part of said carrier in a direction substantially parallel to the axis of the projected light rays, said arm consisting of a plate, and a leaf spring mounted beneath said plate with the ends of the spring resiliently forced toward said plate.

5. In a device of the type described comprising a diagnostic instrument carrier, means for securing thereto light projection mechanism, said carrier having an arm extending outwardly and

- upwardly from the part of the carrier to which the light projecting mechanism is secured, said arm constituting a plate having longitudinal downwardly extending flanges, a pin secured between said flanges, and a leaf spring retained by said pin with the ends of the spring resiliently forced toward the plate. 5
6. A device of the type described comprising a tubular member having a light bulb secured directly to and extending beyond one end thereof, a lens cap fitting over said tubular member and said light bulb, a condensing lens carrying tube extending upwardly and outwardly from said cap and from the top thereof, an inspection lens supporting tube extending outwardly and downwardly from said cap with its axis substantially parallel to the axis of said lens carrying tube, a diagnostic instrument carrier secured to said tubular member, means for adjustably locking said lens cap to said tubular member, and an arm extending outwardly and upwardly from said carrier at substantially the same angle as the angle at which the lens carrying tube extends from the lens cap. 10
7. A device of the type described comprising a tubular member having a light bulb secured directly to and extending beyond one end thereof, a lens cap fitting over said tubular member and light bulb, a condensing lens carrying tube extending upwardly and outwardly from said cap and from the top thereof, an inspection lens supporting tube extending outwardly and downwardly from said cap from the opposite side of said cap, a diagnostic instrument carrier secured to said tubular member, means for adjustably locking said lens cap to said tubular member, an arm extending outwardly and upwardly from carrier at substantially the same angle as the angle at which the lens carrying tube extends from the lens cap, and a resiliently expansible ring-like socket extending substantially at right angles to said arm. 15
8. A device of the type described comprising a tubular member having a light bulb secured directly to and extending beyond one end thereof, a lens cap fitting over said tubular member and light bulb, a condensing lens carrying tube extending upwardly and outwardly from said cap and from the top thereof, an inspection lens supporting tube extending outwardly and downwardly from the opposite side of said cap, a diagnostic instrument carrier secured to said tubular member, means for adjustably locking said lens cap to said tubular member, an arm extending outwardly and upwardly from said carrier at substantially the same angle as the angle at which the lens carrying tube extends from the lens cap, a resiliently expansible ring-like socket extending substantially at right angles to said arm, and an instrument having an annular part held in said socket. 20
9. A device of the type described comprising a tubular member having a light bulb secured directly to and extending beyond one end thereof, a lens cap fitting over said tubular member and light bulb, a condensing lens carrying tube extending upwardly and outwardly from said cap and from the top thereof, an inspection lens supporting tube extending outwardly and downwardly from the opposite side of said cap, a diagnostic instrument carrier secured to said tubular member, means for adjustably locking said lens cap 25
- to said tubular member, and an arm extending outwardly and upwardly from said carrier at substantially the same angle as the angle at which the lens carrying tube extends from the lens cap, said arm constituting a plate and spaced members resiliently forced toward the bottom of said plate for holding a tongue depressor between said members and the plate. 5
10. A device of the type described comprising a tubular member, a source of light rays secured directly to and extending beyond one end thereof, a lens cap fitting over said tubular member and said source of light rays, said cap having a lens therein for projecting rays of light directly from said source outwardly at an angle to the axis of said tubular member, and an instrument carrier secured to said tubular member. 10
11. A device of the type described comprising a tubular member having a source of light rays secured directly to and extending beyond one end thereof, a lens cap fitting over said tubular member and said source of light rays, a cylinder extending upwardly and outwardly near the top of said lens cap, a condensing lens in said cylinder for projecting light rays directly from said source, and an instrument carrier secured to said tubular member. 15
12. A device of the type described comprising a diagnostic instrument carrier, a tubular member secured to said carrier and having a light bulb secured directly to and extending beyond one end thereof, a lens cap fitting over said tubular member and said bulb, said lens cap being slideable longitudinally of and rotatable about said tubular member, means for adjustably securing said lens cap to said tubular member, and a condensing lens in said lens cap for projecting rays directly from said bulb in an upwardly and outwardly direction relative to the axis of said tubular member. 20
13. A device of the type described comprising a diagnostic instrument carrier, a tubular member secured to said carrier and having a light bulb secured directly to and extending beyond one end thereof, a lens cap fitting over said tubular member and said bulb, a condensing lens carrying tube extending upwardly and outwardly from said cap for projecting light rays directly from said bulb, an inspection lens support secured to said cap, and an inspection lens in said support with the axis of said inspection lens substantially parallel to the axis of said lens carrying tube. 25
14. A device of the type described comprising a diagnostic instrument carrier having a cylindrical portion, a tubular member secured to said carrier and having a light bulb secured directly to and extending beyond one end thereof, a lens cap fitting over said tubular member and said bulb, a condensing lens carrying tube extending upwardly and outwardly from said cap for projecting light rays directly from said bulb, a tube extending outwardly and downwardly from said cap at substantially the same angle of inclination as that of said lens carrying tube, a lens support removably secured to said outwardly and downwardly extending tube, and an arm extending outwardly from said carrier substantially parallel to the lens carrying tube. 30
